UNITED STATES PATENT OFFICE.

HERBERT A. Vining, of Arlington, Massachusetts, assignor to Milton Chemical Company, of East Cambridge, Massachusetts, a Corporation of Massachusetts.

MOP.

1,286,455.

Specification of Letters Patent.

Patented Dec. 3, 1918.

Application filed October 31, 1917. Serial No. 199,543.

To all whom it may concern:

Be it known that I, HERBERT A. Vining, a citizen of the United States, residing at Arlington, county of Middlesex, Commonwealth of Massachusetts, have invented certain new and useful Improvements in Mops, of which the following is a specification.

This invention relates to mops, and particularly to the mop head structure and the 10 means for clamping the mop material to the mop head.

The object of my invention is to provide a simple, inexpensive and attractively designed mop head and clamp for reliably 15 clamping the mop material in place, so constructed and arranged as to dispose the entire working face of the mop in a plane parallel to the floor or other surface being cleaned. This object and certain other advantages which will appear more particularly hereinafter are secured in the device 20 of the present invention, the construction and operation of which is fully explained in the specification which follows, illustrated 25 in the accompanying drawings, and particularly pointed out in the appended claims. Throughout the specification and drawings, like reference characters are correspondingly employed, and in the drawings:

30 Figure 1 is a top plan view of a mop head in accordance with my invention.

Fig. 2 is a bottom plan view thereof.

Fig. 3 is a longitudinal section through the 35 mop head on the line 4—4 of Fig. 2, showing in dotted lines the position of the clamp retaining fingers before clenching, and

Fig. 4 is a detail view of the resilient mop material clamping member removed, the 40 resilient character of said member being indicated by the solid and dotted line showing.

I have indicated at 1 a mop head and at 2 any suitable mop material adapted to be clamped to said head.

According to this invention, the mop material 45 2 is adapted to be clamped to the head 1 in such manner as to present a substantially flat working face to the floor. Each individual strand of the mop material is therefore clamped to the head at substantially 50 its center so that the strands are doubled upon themselves and have their free ends exposed as flat mopping surfaces.

As here shown the head 1 is of triangular 55 shape and is so drawn or otherwise shaped as to slope downwardly in three directions

from its center producing a head of general pyramidal form. This construction provides an internal cavity in which a portion of the mop material may lie. The upwardly inclined seat 1¹ formed by the pyramidal shape of the head is cut out to receive a generally spherical socket member or cup 3 which may be rigidly secured to the head 1 by upsetting its inner end to form a flange 4 by means of which the cup may be soldered to the internal face of the head. The inclined seat 1¹ of the generally pyramidal head provides for the connection of the handle with the head at an angle, whereby the working face of the mop is disposed in a plane parallel to the floor or other surface to be mopped, and the entire working face of the mop thus exposed, while the handle itself extends at an oblique angle to the floor.

The handle may be secured to the head by 75 means of a bolt 5 set through the socket member or cup 3 at substantially right angles to the plane of the seat 1¹, and carries on its inner end a securing flange 6 which may be curved to conform to the curvature 80 of the internal surface of the cup 3 and may be secured to the bolt within said cup in any suitable manner as by hammering over the head of the bolt, (see Figs. 2 and 3). The opening in the cup 3 through which the 85 bolt 5 passes may be concealed by any suitable shield 6¹ which is preferably run down upon the bolt until it abuts the socket member 3 and there made fast to the bolt in any desired manner.

The mop material is adapted to be clamped to the head 1 within the perimeter thereof and at the centers of the individual strands. For this purpose the perimeter of the head is bent downward to provide a substantially 95 vertical edge 7 against the inner face of which the material may be clamped by a clamping member 8 which may be held to the head internally thereof by a series of spaced depending fingers 9 formed along 100 the edge 7 (see dotted line showing Fig. 3), and adapted to be clenched down over the clamp 8, (see solid line showing Fig. 3). The clamp 8 may be a simple wire bent to a substantially triangular form and adapted 105 to snugly fit the internal face of the head against the clamping edge 7 thereof. By making the clamp of resilient material (see Fig. 4) the operation of forcing the clamp to its seat 7 puts the clamp under tension 110

and this tension not only assists to maintain the clamp in place due to the tendency of the wire to expand, but causes the wire to firmly clamp the mop material between it 5 and the edge 7 of the head. This clamping action is best illustrated in Fig. 2 wherein the mop material is shown as clamped at the centers of its individual strands between the clamping wire and the edge 7 of the head, 10 and the retaining fingers are shown as bent down over the clamping wire.

It will thus be observed that the head 1 may be formed as a simple stamping into which the spherical cup 3 and bolt 5 may 15 be readily set at the proper angle, and that the clamping member 8 readily seats within the vertically disposed edge 7 of the head and by reason of its resilient nature not only tends to lodge itself therein, but 20 acts to firmly clamp the mop material to the head.

Various modifications in the form and construction of my device may obviously be resorted to if within the limits of the ap- 25 pended claims.

What I therefore claim and desire to se-
cure by Letters Patent is:

1. A triangular sheet metal mop head 30 having a raised semi-spherical portion extending above the upper surface thereof, and a downwardly extending peripheral flange, said semi-spherical portion constituting a seat for a handle connection, and a triangular shaped length of resilient wire 35 expansibly lodged within said head and adapted to clamp strands of mop material against said flange.

2. A sheet metal mop head having a downwardly extending peripheral flange 40 against the internal face of which strands of mop material are adapted to be clamped, and a resilient clamping member shaped to conform to the shape of said mop head at said flange, and adapted to be compressed 45 and lodged within said head and tending

when released to expand and clamp the mop material between itself and said flange.

3. A triangular sheet metal mop head having a raised seat portion extending above the upper surface thereof and a downwardly 50 extending peripheral flange, the working face of the mop head being substantially flat, and said seat portion adapted to receive a handle connection, a triangular shaped length of resilient wire expansibly 55 lodged within said head and adapted to clamp the individual strands of a body of mop material at their centers between itself and the peripheral flange of the mop head, and fingers on said flange adapted to be 60 clenched over said wire to retain it in place.

4. A sheet metal mop head having a downwardly extending peripheral flange against the internal face of which mop material is adapted to be clamped, and a 65 length of resilient wire shaped to conform to the mop head at said flange and adapted to be compressed and lodged within said head and tending when released to expand and clamp the mop material between itself 70 and said flange.

5. A mop head having a seat portion for a handle connection raised above the upper surface thereof and having a downwardly extending peripheral flange, against 75 the internal face of which strands of mop material are adapted to be clamped, and a resilient clamping member shaped to conform to the shape of said mop head at said flange, and adapted to be compressed and 80 lodged within said head and tending when released to expand and clamp the mop material between itself and said flange.

In testimony whereof I affix my signature in presence of two witnesses.

HERBERT A. VINING.
